UNITED STATES PATENT OFFICE.

JOHN S. HOLLIDAY, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA.

ELECTRIC SIGNALING SYSTEM FOR RAILWAYS.

No. 917,763.

Specification of Letters Patent.

Patented April 18, 1903.

Application filed January 30, 1903. Serial No. 413,392.

To all whom it may concern:

Be it known that I, JOHN S. HOLLIDAY, of Wilkinsburg, Allegheny county, Pennsylvania, have invented a new and useful 5 Electric Signaling System for Railways, of which the following is a full, clear, and exact description, reference being had to the accompanying drawings, forming part of this specification, in which—

10 Figures 1, 2 and 3 are diagrammatic representations showing two different embodiments of my invention.

My invention has relation to electric signaling systems for railways, and more 15 particularly to that class of such systems in which the track rails, instead of being divided into insulated blocks or sections as in the usual practice, are electrically continuous for all currents, both propulsion and 20 signaling. Such a system is described and broadly claimed in the pending application of L. H. Thullen, originally filed August 22nd, 1904, Serial No. 221,773, renewal filed March 5th, 1906, Serial No. 304,262.

25 An object of the present invention is to provide means whereby the relays which control the signaling operating circuits will not be effected either by the propulsion currents or by currents from any other source 30 except that which proceeds from the source which is intended to operate them.

Other objects and advantages of the invention will hereinafter appear.

The precise nature of my invention will be 35 best understood by reference to the accompanying drawings, in which I have shown diagrammatically two different forms thereof, and which will now be described, it being premised, however, that the invention 40 is susceptible of various other embodiments without departing from its spirit and scope as defined by the appended claims.

Referring first to the diagram shown in Fig. 1, the numerals 2, 3 and 4 designate a 45 two-phase transmission line from which the current for operating the relays is derived. 5 and 6 designate the track rails which, as above stated, instead of being divided into insulated blocks or sections in the usual 50 manner, are electrically continuous for all currents, both propulsion and signaling. The terms "section" and "division" as employed herein and in the claims, do not, therefore, refer to insulated divisions or sec- 55 tions of these rails, but are merely used for

convenience to designate the portions of the track between adjacent signals. These rails are supplied with a two-phase current derived from the two-phase transmission line through the two-phase transformers 7 and 8, one transformer being shown for each of the two track sections or divisions illustrated. These transformers each have two secondary coils or windings 9 and 10, the coil 9 being connected by one terminal to the rail 6, and the coil 10 being connected to the rail 5. The other terminals of these two coils are connected to a common return conductor 11, leading to the relays. The four relays shown are designated by the respective numerals 12, 13, 14 and 15, there being two of these relays shown for each track section or division. Each relay has two coils or windings 16 and 17, the coil 16 being connected by one terminal to the rail 6 and the coil 17 being connected to the rail 5. 18 designates the movable members of these relays, which are arranged to control the local signaling circuit 19 through the contacts 20. The two sets of contacts 20 for each track section or division are in series with each other, as shown. 21 and 22 designate the respective semaphores and signals for the respective track sections or divisions, which signals are controlled by the local circuits 19 in the usual manner.

The operation is as follows:—The movable members 18 of the relays when no trains are in the divisions hold the contacts 20 closed, and the semaphores or signals 21 and 22 at 90 clear positions. That is to say, these relays operate to close the local circuits and clear the signals when positively actuated by current flowing through coils 16 and 17, while they open and set the signals at danger 95 whenever the coils 16 and 17 cease to act effectively. It will be seen that while the coils 16 and 17 of each relay are in parallel relation to each other with respect to the transformer of the same track section or division, so that each coil or winding will carry one phase of the current impressed upon the track rails by the transformer, yet that by reason of their connection to the common return conductor 11 leading to the common 100 junction of the secondary coils of the transformer, said coils or windings 16 and 17 are in series relation to each other both with respect to any propulsion current which may tend to flow therethrough from one rail to 110

the other by reason of a difference in potential in the two rails; and also with respect to any current which may tend to flow therethrough from any other transformer. By 5 reason of this series connection of these coils with respect to propulsion currents and to the currents from any other transformer, except the one which is intended to operate them, it will be readily seen that the relays 10 will not be affected in any way by stray currents from any source and that they will only operate by a two-phase current from their own transformer. Supposing a train to be 15 traveling from right to left and having a clear track ahead, as the train approaches the relay 15 that relay will be short-circuited, and the signal 22 will be set at danger. Inasmuch as the contacts controlled by the two 20 relays 14 and 15 are in series with each other in the local signaling circuit, it will be seen that the signal 22 will remain at danger so long as either of these relays is short-circuited by the train, or in other words, while the train is in that division, since it is always 25 between the transformer and one of the relays. The train will retain its control of the relay 14 until it gains control of the relay 13. After it has gained control of the relay 13 it will lose its control of the relay 14 and the signal 30 22 will clear. As soon as the train gains control of the relay 13, the signal 21 will be set at danger, and will remain at danger so long as the train is in that section or 35 division of the track and controlling either of the relays 12 and 13.

It will be understood that the relays can be adjusted or tuned so that trains will retain and lose control thereof at any desired distance therefrom, this depending upon the 40 impedance of the rails, the power factor of the system, and various other conditions well known to signal engineers and which must be determined by them in each case in accordance with the usual practice.

45 Inasmuch as there is no exactly defined points in the track which separate adjacent sections or divisions thereof, there will necessarily be some overlap which will make it necessary to set the signals somewhat in advance of the rail defining points of the divisions or sections, so that the signal guarding the entrance to any particular section or division will not go to danger in the face of the train. That is to say, the signal 21 will go to 50 danger at such time as the train has gained control of the relay 13 by short-circuiting that relay, and the signal 21 must be set sufficiently behind the relay 13 so that the train will have passed or be passing said signal at the time it gains control of said relay.

The arrangement shown in Fig. 2 is similar to that shown in Fig. 1, except that instead of employing a two-phase transmission line, I employ a single-phase transmission line 23 with single-phase transformers 24. The

secondaries of each of these transformers are connected with the respective track rails 5^a and 6^a by a branched circuit 25 and 26, one of these branches, as the branch 25, having therein a capacity 27, and the other 70 branch having an impedance coil, or other impedance device, 28. By this arrangement the current delivered by the secondaries of the transformers will be split into a two-phase current, one phase of which will be 75 delivered to each of the track rails in the same manner as in the arrangement shown in Fig. 1. The relays in this case are three-phase relays having each two coils 16^a and 17^a arranged in the same manner as the coils 80 16 and 17 of the relays first described and having a third coil or winding 29 which is connected directly across the two-phase transmission line 23, the purpose of this third coil or winding being to reduce the 85 power required for operating the relays to be transmitted over the rails. The other parts of the system shown in Fig. 2 not specifically referred to are designated by the same reference numerals as the corresponding parts in 90 the system of Fig. 1.

In the arrangements above described, I have shown each track section or division as provided with two relays, one at each end portion thereof, with an intermediate transformer. In the arrangement shown in Fig. 3, however, there is but one relay for each track section or division, the transformer being placed near the entrance to the division, and the relay near the opposite end. 100 This relay is shown at 30 and the transformer at 31. 32 indicates diagrammatically a train in one of the divisions. The other numerals are the same as those employed in Fig. 1 to designate corresponding parts. 105

The advantages of my invention are many, and will be apparent to those skilled in the art. The use of the track rails which are electrically continuous for all currents avoids the necessity for the expensive cross-bonding 110 which is required in the old block systems where electric propulsion is employed. The relays are of simple character together with the circuits therefor, and are of such character, as before described, as to be absolutely 115 unaffected by any currents except those which are intended to operate them. Either direct or alternating current may be employed as the propulsion current.

I claim:

1. In an electric signaling system, track rails which are electrically continuous for all currents, means for impressing polyphase currents on said rails, and signal-controlling relays connected to the rails, each relay having windings which are in parallel with respect to the currents impressed upon the track rails of the particular division of the track to which that relay is connected, but which are in series with respect to any pro- 120 125 130

pulsion current which may flow there-through, and also with respect to currents impressed upon other adjacent portions of the rails; substantially as described.

- 5 2. In an electric signaling system, track rails which are electrically continuous for all currents, means for impressing two-phase currents upon said rails, and signal-controlling relays connected to the rails, each relay having windings which are in parallel with respect to the currents impressed upon the track rails of the particular division of the track to which that relay is connected, but which are in series with respect to any propulsion current which may flow there-through, and also with respect to currents impressed upon other adjacent portions of the rails; substantially as described.
- 10 3. In an electric signaling system, track rails which are electrically continuous for all currents, means for impressing two-phase currents upon the rails, and signal-controlling relays having two coils connected one to each track rail and both connected to a common return conductor leading to the source of their operating current; substantially as described.
- 15 4. In an electric signaling system, track rails which are electrically continuous for all currents, a plurality of relays for each signal, a transformer for each signal, and means whereby each transformer impresses a two-phase current upon the adjacent portions of the track rails, each relay having two coils which are connected by one terminal to different track rails, and by their other terminals to a common return to the secondary of the transformer; substantially as described.
- 20 5. In an electric signaling system, track rails which are electrically continuous for all currents, a plurality of relays for each signal, a transformer for each signal, and means whereby each transformer impresses a two-phase current upon the adjacent portions of the track rails, each relay having two coils which are connected by one terminal to dif-
- ferent track rails, and by their other terminals to a common return to the secondary of the transformer, together with a signal-controlling circuit for each signal controlled by said relays, said relays having their controlling contacts in series in said circuit; substantially as described.
- 25 6. In an electric signaling system, track rails which are electrically continuous for all currents, transformers for impressing two-phase currents on said rails, and signal-controlling relays each of which has two windings which are in parallel with their own transformer, but which are in series with each other with respect to the circuit of other transformers; substantially as described.
- 30 7. In an electric signaling system, track rails which are electrically continuous for all currents, means for impressing two-phase currents upon said rails, one of said rails carrying one phase of the current, and the other rail carrying the other phase of the current, and suitable controlling relays having each two windings which are connected across the track rails in series, and also by a common return conductor with the source of their operating current, all the relays for any particular track division having their signal-controlling contacts in series with each other; substantially as described.
- 35 8. In an electric signaling system, track rails electrically continuous for all currents, a two-phase relay and a source of two-phase current in each block, said relay having one of its windings connected to said source by one track rail and a common return wire, and the other winding connected to said source by the opposite track rail and the common return wire; substantially as described.
- 40 9. In testimony whereof, I have hereunto set my hand.

JOHN S. HOLLIDAY.
